DESIGN FOR A DRESS

Concetta Jaccarino, New York, N. Y., assignor to
C. H. D. Robbins Co. Inc., New York, N. Y., a corporation of New York

Application March 31, 1934, Serial No. 51,280

Term of patent 3½ years

To all whom it may concern:

Be it known that I, CONCETTA JACCARINO, a citizen of the United States, residing at New York, county and State of New York, have invented a new, original, and ornamental Design for a Dress, of which the following is a specification, reference being had to the accompanying drawing, forming a part thereof.

The figure of the drawing is a front perspective view of a dress showing my design.

The rear of the garment is plain with the exception that the ruffles about the collar and cuffs extend entirely around the back of the respective elements.

I claim:

The ornamental design for a dress, substantially as shown and described.

CONCETTA JACCARINO.
